Primary Examiner — Kevin K. Rudzinski*Assistant Examiner* — Clare Ann Gannon(74) Attorney, Agent, or Firm — Banner & Witcoff, Ltd.(57) CLAIM

The ornamental design for a belt, as shown and described.

DESCRIPTION

FIG. 1 is a top, front, right perspective view of a belt showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The even-length broken lines represent stitching. The uneven-length broken lines represent boundaries that form no part of the claimed design. The unshaded surface within the uneven-length broken lines forms no part of the claimed design. The contrasting shading of the rectangle in FIGS. 3 and 5 represents a hook-and-loop fastener.
